FOLDING WING

Ignacio Izsak and Vincent Buletish, Chicago, Ill.

Application December 21, 1932, Serial No. 648,224

3 Claims. (Cl. 244—12)

The invention relates to improvements in folding wings, in association with an airplane.

The main object of the invention is to provide a novel folding wing construction having hinged and rotating means to fold the wings.

Another object of the invention is to provide a novel folding wing construction having locking means to secure safety for the wings, when flying.

A further object of the invention is to provide a novel folding wing construction having hinged and sliding means for the struts to permit the easy folding of the wings.

A still further object of the invention is to provide a novel folding wing construction to permit a reduced storage space for the airplane in the hangar.

A still further object of the invention is to provide a novel folding wing construction, which will be compact, simple, easily assembled and efficient in carrying out the purpose for which it is designed.

With the foregoing and other objects in view, which will appear as the description proceeds, the invention consists in certain novel features 25 of construction, arrangement, and combination of parts, hereinafter more fully described, illustrated in the accompanying drawings, and particularly pointed out in the appended claims.

It is to be understood that various changes in 30 the form, proportion, size and minor details of the structure may be made without departing from the spirit or sacrificing any of the advantages of the invention.

For the purpose of facilitating an understanding of our invention we have illustrated in the accompanying drawings preferred embodiments thereof, from an inspection of which, when considered in connection with the following description, our invention, its mode of operation, assembly, and many of its advantages should be readily understood and appreciated.

Referring to the drawings, in which similar characters of reference are employed to indicate corresponding or similar parts throughout the 45 several figures in the drawings:—

Figure 1 is a top plan view of the framework of the folding wing, ready to be locked, the covering being removed in order to show the locking device inside of the wing.

Figure 2 is a cross sectional view of the framework of the folding wing taken approximately on the line 2—2 of Fig. 1, showing the locking mechanism inside of the wing structure.

Figure 3 is a fragmentary front elevational 55 view of the folding wing construction.

Figure 4 is an assembled elevational view of the control wheel to manipulate the cables to effect the folding of the wing.

Figure 5 is a fragmentary sectional view of the grooved portion of the control wheel on the line 5 5—5 of Figure 4.

Figure 6 is an assembled elevational view of the disconnecting means of the cables leading to the ailerons on the line 6—6 of Figure 1.

Figure 7 is a top sectional view on the line 7—7 10 of Figure 6.

Figure 8 is a fragmentary top elevational view of a folding wing ready to be locked, full lines indicating when in flight, and dotted lines indicating when wing is folded rearward alongside 15 the fuselage.

Figure 9 is an enlarged top plan view and fragmentary sectional view of the locking means to secure the front spar of the wing to the top 20 longeron.

Figure 10 is an enlarged top plan view and fragmentary sectional view of the hinged and rotating means to secure the rear spar of the wing to the top longeron.

Figure 11 is an enlarged elevational view of the 25 hinged and pivotal means to secure the lower ends of the front and rear strut to the bottom longeron.

Figure 12 is an enlarged sectional view on line 12—12 of Figure 11.

Figure 13 is a fragmentary end sectional view on line 13—13 of Figure 12.

Figure 14 is a fragmentary elevational view of the hinged means to secure the upper end of the rear strut to the rear spar.

Figure 15 is a fragmentary end sectional view on line 15—15 of Figure 14.

Figure 16 is a fragmentary front elevational view of the hinged and sliding means to permit the upper end of the front strut to slide forward 40 when the wing is folded.

Figure 17 is a cross sectional view on line 17—17 of Figure 16.

Figure 18 is a cross sectional view on line 18—18 of Figure 16.

Figure 19 is an assembled top plan view of the disconnecting means and of the locking device to secure the front spar of the wing to the top 45 longeron.

Figure 20 is an end cross sectional view on line 50 20—20 of Figure 19.

Figure 21 is a fragmentary cross sectional top view on line 21—21 of Figure 20.

Figure 22 is an assembled end elevational view of the locking device inside of the wing structure.

The drawings refer only to the right hand wing. The left hand wing is not shown. Its folding operation is identical to the right hand wing.

Referring to the drawings more specifically, 1 5 denotes the right hand top longeron of a fuselage, 2 the framework of a wing of standard construction, 3 the ribs of the wing, 4 the front spar of the wing, 5 the rear spar of the wing, 6 the front strut, 7 the rear strut.

10 The rear spar 5, is covered with a sheet steel ferrule 20, at its inner end and is made fast by bolts 21, and nuts 22. The rear spar 5, is cut out at its inner end for the receipt of the offset portion 23, threaded projection 24, safety nut 25, and 15 cotter pin 26, of the hinge 173 projecting through a hole drilled at the center of the back wall of the ferrule 20, to provide a rotatable mounting of the rear spar 5, on the offset portion 23. This forms the wing half of the connecting hinge.

20 The eye of hinge 173 is fastened to the fuselage hinge member 174 by means of the eyebolt 27, and safety nut 33. The fuselage hinge member 174 is brazed to the fitting 28, is wrapped around the vertical fuselage strut and is made secure by the 25 tightening of the tension bolts 31, passing through its flanges 30 30, by the nuts 32. This forms the fuselage half of the connecting hinge (Figure 10).

25 The front spar 4, is covered with a steel forging fitting 13, at its inner end very carefully machined and reduced in weight, and is made fast by bolts 14, and nuts 15. Fitting 13, has a T-shaped projection 16, at its front end. The web part of the T-shaped projection 16, is provided with a 30 drilled hole 19, and at its bottom with the flange 17. This forms the wing half of the locking means.

30 The T-shaped projection 16, of the fitting 13, fits into the inside of the housing 12, a steel forging very carefully machined. The housing 12, is brazed to fitting 8, is wrapped around the top longeron 1, and the vertical fuselage strut (S) and is made secure by tightening of the tension bolts 10, passing through flanges 9 9, by nuts 11.

35 The side flanges 29 29, of the housing 12, are provided with the holes 18 18, in line with the hole 19, of the web of the T-shaped projection 16, to facilitate the locking of the wing. This forms the fuselage half of the locking means (Figure 9).

40 The rear strut 7 is covered with a sheet steel ferrule 36, at its lower end, and is made fast by bolts 34, and nuts 35. The ferrule 36, has a projection 37, terminating in a horizontal part 38, provided with a hole to permit the passage of the 45 pivot bolt 41, held in position by the nut 85.

45 The front 6, is covered with a sheet steel ferrule 39, at its lower end, and is made fast by the bolts 83, and the nuts 84.

50 The ferrule 39, has a forked projection 40, at a suitable oblique angle, provided with holes to permit the passage of the bolt 52, held in position by the nut 53.

55 The bracket 53, has a flange 42, at a suitable oblique angle, conforming to the angle of the forked projection 40. The flange 42, fits between the sides of the forked projection 40, and is provided with a hole in line with the holes in the sides of forked projection 40, to permit the passage of the hinge bolt 52.

60 The bracket 43, has another projection 44, conforming to the shape of the projection 37, and the horizontal part 38, of the ferrule 36, and are joined together by the rivet 165. This forms the struts half of the connecting hinge.

65 70 75 The clevis 45, is brazed to the fitting 46, is

passed around the bottom longeron 47, and is wrapped around the vertical fuselage strut 48, and is made secure by tightening the tension bolts 50, passing through its flanges 49 49, by nuts 51. The flanges 141 141, and the tension bolts 154 are provided for the attachment of the fitting of the chassis strut. This forms the fuselage half of the connecting hinge (Fig. 11, and Fig. 12).

70 The rear strut 7, is covered with a steel forged fitting 54, at its upper end, and is made fast by bolts 64, and nuts 65. The fitting 54, has an upturned projection 55, with a hole in its end. Projection 55, is hinged between the forked part of 75 56 56, of the bracket 57, by means of bolt 60, and nut 61. Bracket 57, passes around the rear spar 5, and is made fast by the bolts 58, and the nuts 59 (Fig. 14, and Fig. 15).

75 The front strut 6, is covered with a steel forged fitting 62, at its upper end, and is made fast by the bolts 66, and the nuts 67.

80 The fitting 62, has a twisted and upturned forked projection 63, with holes provided for the receipt of bushing 69. One end of the arm 68, is mounted on the bushing 69, between the forked part of projection 63. The rounded end of the 85 arm 68, fits between the recess of the sliding carriage 70, and is held in place by the bolt 71, and nut 74.

85 The sliding carriage 70, by means of its top flange 72, is able to slide on the inside lower flanges of an inverted track 73, which has an opening at its bottom, to permit the unobstructed sliding of the web part of the carriage 70. The inverted track 73, has a slightly inclined part with enlarged depth at its inner end to facilitate an easy start for the carriage 70, when the wing has to be folded.

90 The track 73, is secured to the bottom part of the front spar 4, by the screws 170.

95 The carriage 70, has an eyelet at its inner end, to attach the cable 74, guided in the groove 75, of the arm 68, and leading through the guide sheaves 124, and 125 respectively, to the groove 120, of the control wheel 118, being securely fastened to it at a suitable place.

100 The bottom flange 93, of a suitable bracket 92, is fastened at a convenient place to the upper part of the bottom of the rib 3, nearest to the fuselage, by means of the screws 153 153.

105 The top flange 91, of the bracket 92, supports the equalizer 90, by means of a double wedged shaped conical pin 86, which has a bottom flange 87, resting on the top of the equalizer 90, a threaded projection 89, with a square portion 88, that fits into the square hole of the equalizer 90, located at its center.

110 The projection 89, passes through the hole of the top flange 91, and is rotatably retained by the nut 158. The equalizer 90, has eyelets at its ends to attach the cables 99 99, leading to the 115 equalizer 100, inside of the wing structure. This forms the wing half of the disconnecting means of the outer locking mechanism.

120 The conical pin 86, fits inside of the housing 81, open at its bottom. Housing 86, has a top flange 65 82, a threaded projection 83, with a square portion 80. The lever 75, has the knob 76, at one end, and a square hole at its other end, that fits over the square portion 80, of projection 89. The operating lever 75 is rotatably retained between the flange 82, and the horizontal flange of the bracket 85, by the nut 58. The bracket 85, is secured to the top longeron 1, by screws 156.

125 The spring lever 77, is secured to the top of 75

the operating lever 75, by means of the rivets 18. The plunger 79, is secured at a suitable place to the spring lever 77, by the nut 162, and projects in the hole 170, and 171 respectively of the plate 172.

5 The connecting rod 94, is secured at one end to the lower projection 161 of the knob 76, by the nut 163. At its other end it is secured to the lock pin 95, by the screw 96.

10 The lock pin 95, has a round projection 97, which guides the pin during the locking of the wing. The projection 97, is supported in the flange 98, of the bracket 164, made fast to the top longeron 1, by means of screws 165.

15 The plate 172 is fastened at a suitable place to the bottom part of the top longeron 1, by means of the screws 169, and is provided with two holes 173 and 174 suitably located to accommodate the plunger 79, in its locking and 20 unlocking position. This forms the fuselage half of the disconnecting means and the outer locking mechanism (Fig. 21, Fig. 23, Fig. 24).

25 The equalizer 100, has eyelets at its ends to attach the cables 99 99, leading from the equalizer 90. It is mounted at a suitable place on the plate 101, secured in the recess of the tie board 102, made fast to the upper parts of the bottoms of two adjacent ribs 115, 115.

30 Equalizer 100, is pivotally mounted on the bolt 103, and held in place by the nut 104.

35 Equalizer 100, has a projection 105, at its outer end which is connected to a bent connecting rod 106, by means of the bolt 107, and the nut 108. The other end of the connecting rod 106, is secured to the lock pin 109, by the screw 110. The lock pin 109, fits the inside of the bushing 69.

40 The lock pin 109, has a round projection 111, is guided in the flange 112, of the bracket 113, screwed to the bottom of the rib 115, by the bolts 116, and the nuts 117. This forms the locking mechanism inside of the wing structure 2 (Fig. 22).

45 The folding wheel 118, is provided with grooves 119, and 120, for the reception and to secure the cables 74, and 121, respectively, performing the folding of the wing.

The cable 74, leads by means of the guide sheaves 124, and 125, to the eyelet of the sliding carriage 70, of the front strut 6.

50 The cable 121, leads by means of guide sheave 123, suitably located at the tail end of the fuselage, to the attachment 122, of the rear strut 7.

55 The folding wheel 118, is supported by the brackets 126, secured to a vertical member of the fuselage 152 and to a horizontal member of the fuselage 153, at suitable places by the bolts 127. The bent operating lever 128, is fastened to the outside flange 154, of the folding wheel 118, by the countersunk bolts 129, and the nuts 130.

60 The knob 131, is secured to the top projection of the lever 128, to rotate the wheel.

The operating lever 128, is pivotally mounted on the pin 134, secured in the plate 132, fastened to the vertical member 152, and the horizontal member 153, of the fuselage by wood screws 133.

65 The operating lever is retained on the pin 134, by the washer 135, and the nut 136 (Fig. 4 and Fig. 5).

70 The bottom flange 150, of a suitable bracket 149, is fastened at a convenient place to the upper part of the bottom of the rib 3, nearest to the fuselage 1, by means of screws 151, 151. The top flange 148, of the bracket 149, supports the 75 equalizer 137, by means of a double wedged

shaped conical pin 145, which has a bottom flange 146, resting on top of the equalizer 137, a round threaded projection 147, with a square portion 138, that fits into the square hole of the equalizer 137, located at its center. The projection 147, passes through the hole of the top flange 148, and is rotatably retained by the nut 157.

5 The equalizer 137, has eyelets at its ends to attach the cables 159 159, leading to the ailerons. This forms the wing half of the disconnecting means of the ailerons.

The double wedged shaped conical pin 145, fits inside the housing 139, open at its bottom. The housing 139, has a top flange 140, and a round threaded projection 141, with a square portion 15 160.

The arm 161, has a square hole at one of its ends, that fits over the square portion 160. The arm is rotatably retained between the top flange 140, and the horizontal flange 158, of the bracket 20 142, by the nut 144. The bracket 142, is made fast at a suitable place to the side of the top longeron 1, by means of the screws 143 143. The arm 161, has two eyelets at its other end to attach the cables leading to the control sticks. This 25 forms the fuselage half of the disconnecting means of the ailerons (Fig. 6 and Fig. 7).

How the folding of the wings is accomplished:

When the machine has to be shipped, or removed to the hangar after a flight, the pilot 30 with one of his fingers lifts the spring 77, by means of the plunger 79, from the hole 171, of the plate 172. Taking hold of the knob 76, with his other finger, the operating lever 75, is rotated to the right, until the plunger 79, enters 35 the hole 170 of the plate 172. During the rotation the connecting rod 94, withdraws the lock pin 95, from the hole 19, of the web of the T-shaped projection of the fitting 13. Simultaneously the operating lever 75, rotates the housing 40 81, by bearing on its square portion 80. Housing 81, in turn rotates the double wedged shaped conical pin 86, which by its square portion 88, is oscillating the equalizer 90. The latter, by the cables 99 99, produces harmonious oscillations in 45 the equalizer 100, inside of the wing structure, and its projection 105, actuates the bent connecting rod 106, and the latter withdraws the lock pin 109, from within the bushing 69, to such an extent to free the arm 68, and permit the sliding 50 of the upper part of the front strut 6.

When the lock pins 95, and 109, respectively, are withdrawn, the pilot manipulates the folding wheel 118, located in the cock pit by gripping the knob 131, of the lever 128. By rotating the 55 folding wheel 118, clockwise, a pull is produced in the cable 121, compelling the rear strut 7, to rotate on the pivot 41. A corresponding slack in the cable 74, leading to the eyelet of the sliding carriage of 70, of the front strut 6, is enabling 60 the latter to slide forward in the inverted track 73.

The wing begins to rotate downward on the offset portion 23, of the hinge 173.

The T-shaped projection 16, of the fitting 13, gradually slides out from within the housing 12. 65 The double wedged shaped conical pins 86, and 145, slide out from within the housings 81, and 139. This accomplished the wing starts to fold rearward on the hinges of 173 and 174.

The particularly constructed hinged and pivot- 70 al arrangements of the fittings, covering the upper and lower ends of the front strut 6, and the rear strut 7, as set forth, permit the gradual folding of the wing alongside the fuselage.

In case the wing has to be made ready for 75

flying, the folding wheel 118, is rotated anti-clockwise. A pull will be produced in the cable 14, which gradually rotates the wing upward on the offset portion 23, of the hinge 173, until the 5 sliding carriage 70, is brought back to its original position. The corresponding slack in the cable 121, is enabling the wing structure to reach its flying position. The double wedged shaped conical pins 86, and 145, re-enter gradually the housings 81, and 139. The T-shaped projection 16, of the fitting 13, re-enters the inside of the housing 12, and when its bottom flange 17, touches the sides 29 29, of the housing 12, the wing is ready to be locked.

15 By lifting the spring 77, the plunger 79 is removed from within the hole 170, of the plate 172. The operating lever 75, is moved backward to the left, until the plunger 79, enters the hole 171, of the plate 172. Simultaneously the operating 20 lever 75, moves forward the connecting rod 94, which pushes the lock pin 95, into the holes 17, of the web of the T-shaped projection 16, and into the hole 18, of the outer side 29, of the housing 12, locking them securely together.

25 The movement of the operating lever 75, furthermore oscillates the equalizer 90, as set forth, which in turn harmoniously oscillates equalizer 100, inside of the wing structure, and its projection 105, moves forward the bent connecting rod 30 106, which pushes the lock pin 199, within the bushing 69, to such an extent, that it locks the forked projection 63, of the fitting 62, covering the upper end of the front strut 6, to the front part of the arm 68, supported by the front spar 4, 35 of the wing structure 2, making the wing safe for flying.

The exposed part of the locking device inside of the wing can be covered in stream line fashion.

40 The gap between the inner end of the wings and the outside face of the fuselage can be covered with thin sheeting airfoil shape.

What we claim as new and seek to secure by Letters Patent is:

45 1. In an airplane having folding wings, a combination of wing supporting front and rear spars and struts, equipped with means, whereby the wings may be rigidly connected to the fuselage; said front spars having at their inner ends 50 means for disconnecting the inner front por-

tions of the wings from the fuselage, said front struts having at their outer ends means to unlock the rigid connections between the front struts and the outer front portions of the wings, said rear spars and rear struts having at their 5 inner ends means that permit the disconnected wings to rotate backwards, said inner ends of the rear spars terminating in pivots which in combination with the pivotal connections of the rear struts and rear spars permit horizontal rotations of the said disconnected portion of the wings; all of which operations are controlled by suitable means from within the fuselage.

2. In an airplane having folding wings, a combination of wing supporting front and rear spars 15 and struts, equipped with means, whereby the wings may be rigidly connected to the fuselage; said means comprising locking and unlocking devices disposed between the inner ends of the front spars and the fuselage and between the 20 outer ends of the front struts and the outer front portions of the wings; vertical hinges disposed below between the fuselage and the rear struts and above between the fuselage and the inner ends of the rear spars; pivotal connections be- 25 tween the rear struts and the rear spars which in combination with the hinges of the rear spars permit backward and forward rotation of the disconnected wings; the locking and unlocking devices being operated by lever movements while 30 the rotations are produced by means of grooved folding wheels guiding the control cables, all of which operations are performed within the fuselage.

3. An airplane having a fuselage and folding 35 wings attached thereto, said wings having front and rear spars interconnected by transverse ribs, supporting struts for said wings, means to disconnect the wings from the fuselage; said means comprised of upper and lower halves, disposed 40 between the inner ribs and the fuselage; the upper halves of which are shaped as receptacles supported at the sides of the fuselage, while the lower halves are shaped as double wedged conical pins fitting within said receptacles fastened 45 to the bottom portions of the inner ribs and lever elements disposed within the fuselage for operating said means.

IGNACIO IZSAK.
VINCENT BUKLETISH. 50
